UNITED STATES PATENT OFFICE.

NATHANIEL H. HALE, OF STONE, KENTUCKY.

AUTOMATIC CAR STOP.

1,403,116.

Specification of Letters Patent. Patented Jan. 10, 1922.

Application filed July 29, 1920. Serial No. 399,961.

To all whom it may concern:

Be it known that I, NATHANIEL H. HALE, a citizen of the United States, residing at Stone, in the county of Pike and State of Kentucky, have invented certain new and useful Improvements in Automatic Car Stops, of which the following is a specification.

My invention relates to automatic means for stopping cars, particularly mine or pit cars; and a primary object thereof is to prevent such cars from colliding with an upended dump, with consequent damage.

A further object of the invention is to provide an automatic car-stop which is inexpensive to install and which is therefore adapted to use where the amount of material handled is relatively small and does not warrant the installation of an automatic car feeder, though of course the use is not to be thus limited.

A still further object of the invention is to provide an apparatus of this character which is extremely simple in construction and operation, and also one which cannot fail to function properly.

With the above general objects in view, and others which will be obvious to those skilled in the art, from the description hereinafter, my invention consists in the features, details of construction, and combinations of parts, which will first be described in detail in connection with the accompanying drawings and then particularly pointed out in the claims.

In the drawings:

Figure 1 is a side elevation of the complete apparatus, parts being in section to more clearly show the operation, and Figure 2 is a plan view thereof.

The tipple is referred to generally by the numeral 1, and is provided with any preferred form of tilting track section or dumping platform 2. At the forward end of the dumping platform are the usual stop-horns 3 with which the wheels of the pit cars will impinge and prevent the car from running off the dumping platform. This platform is pivoted as shown at 4, and carries the sword 5 adjacent its rear end. All of the construction thus far described is old and per se it involves no invention.

The car-stop and its operative connection with the dumping platform will now be described.

Pivottally mounted as indicated by nu-

meral 6, substantially midway between the tipple rails 7, 7, is a car-stop or bumper 8. The bumper may be of any desired construction and is preferably provided with an iron bumper head 9.

A downwardly extending arm 10 passes through a slot 11 in the bumper and is pivotally mounted therein. At its lower end this arm is pivotally connected as shown at 12 with a link 13 which is itself pivotally attached at 14 to the sword 5. A chain 15, or other suitable supporting means is attached to the rear end of the link 13 and to the tipple platform as shown at 16 and 17 respectively.

A series of holes 18 may be provided in the link 13 for the purpose of adjusting the arm 10, so that the bumper will be at the desired elevation when in operative position.

A rod 19 carrying a coil spring 20 passes through an aperture in the tipple platform and is attached to the car-stop.

If desired, suitable stays 21 may lead from the car-stop pivot for reenforcing the same in case a whole trip should accidentally come upon it.

The operation of the apparatus will now be described with particular reference to Figure 1 which shows in full lines the car-stop, the dumping platform, and its connecting mechanism, in elevated position; while dotted lines show the position of the same elements in lowered position.

For the purpose of describing the operation I will assume that there is no car on the dumping platform and that all elements of the apparatus are in the positions shown by dotted lines.

A pit car is now run onto the tilting section to be dumped, and as the rear end of the tilting section or dumping platform rises the sword 5 will raise and force to the left (Fig. 1) the link 13, which will in turn lift the arm 10, thereby raising the car-stop into operative position. When in this position, if another car should be accidentally run out on the tipple platform it will not strike and damage the dumping platform but it will be engaged and stopped by the bumper 8; the rod 19 and spring 20 acting as a shock absorber.

After the dumping operation the platform 2 will be lowered, and by means of the same operating mechanism previously described, the bumper will be drawn down positively into its inoperative position, whereby the

next car may pass freely over the same onto the dumping platform.

It is to be particularly noted here that the connections between the bumper and the dumping platform are such that the lowering as well as the raising of the bumper is positive so that it is impossible to either raise or lower the dump without the proper functioning of the car-stop.

10 It will be understood, of course, that my invention is particularly adapted to use where an automatic car feeder system has not been installed and hence where cars may be inadvertently run out on the tipple platform when the tilting section is in dumping position. It will be obvious, however, that my invention is also desirable for use as an extra precaution in combination with automatic car feeder installations, so that no 20 damage would result if the feeder system should fail to function properly.

In accordance with the patent statutes I have described what I now believe to be the best embodiment of my invention, but 25 I do not wish to be understood thereby as limiting myself or the scope of my invention, as many changes and modifications may be made without departing from the spirit of the invention, and all such I aim to 30 include in the scope of the appended claims.

What I claim as new and desire to secure by Letters Patent is:

1. An automatic car-stop including a dumping platform, a pivotally mounted bumper located in front of the dumping platform, and a positive connection between the bumper and the dumping platform for elevating and depressing said bumper in accordance with corresponding movements of 40 said dumping platform.

2. An automatic car-stop including a dumping platform, a pivotally mounted bumper located in front of the dumping platform, a positive connection between the bumper and the platform for elevating and depressing said bumper in accordance with corresponding movements of said dumping platform and a shock absorber connected with said bumper.

50 3. An automatic car-stop including a dumping platform, a pivotally mounted bumper located in front of the dumping platform, a positive connection between the bumper and the dumping platform for elevating and depressing said bumper in accordance with corresponding movements of

said dumping platform, a rod carried by the free end of the bumper, and a coil spring carried by the rod, said rod and coil spring acting as a shock absorber.

60 4. An automatic car-stop including a dumping platform, a sword attached thereto, a pivotally mounted bumper located in front of the dumping platform, an arm depending therefrom, a link connecting said arm and said sword, and means for supporting the free end of the link.

5. An automatic car-stop including a dumping platform, a sword attached thereto, a pivotally mounted bumper located in front of the dumping platform, an arm depending therefrom, a link connecting said arm and said sword, means for supporting the free end of the link, and a shock absorber operatively connected with said 75 bumper.

6. An automatic car-stop including a dumping platform, a sword attached thereto, a pivotally mounted bumper located in front of the dumping platform, an arm pivotally connected with said bumper and depending therefrom, a link pivotally attached to said arm and said sword, and means for supporting the free end of the link.

85 7. An automatic car-stop including a dumping platform, a sword attached thereto, a link pivotally connected with said sword, a chain supporting the free end of said link, a pivotally mounted bumper located in front of the dumping platform, and an arm connecting said bumper and said link.

90 8. An automatic car-stop including a dumping platform, a sword attached thereto, a link attached to said sword, means for supporting the free end of the link, a pivotally mounted bumper located in front of the dumping platform, an arm depending therefrom, and means for adjustably and 100 pivotally connecting said arm and link.

95 9. An automatic car-stop including a dumping platform, a sword attached thereto, a link attached to said sword, a flexible element supporting the free end of the link, a pivotally mounted bumper located in front of the dumping platform, a rod carried by said bumper, and a coil spring carried by said rod, an arm attached to and depending from said bumper, and an adjustable connection between said arm and said link.

110 NATHANIEL H. HALE.
